JOHAN FREDRIK OLOF ÖHBORG, OF WIBORG, FINLAND.

INTERNAL-COMBUSTION MOTOR.

1,331,665.

Specification of Letters Patent. Patented Feb. 24, 1920.

Application filed July 5, 1918. Serial No. 243,266.

To all whom it may concern:

Be it known that I, JOHAN FREDRIK OLOF ÖHBORG, a citizen of Finland, residing in Wiborg, Finland, have invented certain new 5 and useful Improvements in Internal-Combustion Motors, of which the following is a specification.

The present invention relates to motors for liquid or gaseous fuel, and aims at the 10 utilization of the greatest possible portion of the energy still remaining in the outgoing combustion gases. This takes place in such manner that the hot combustion gases are led into and through a receptacle filled with 15 water, whereby steam is produced, which is conducted into a second cylinder and in this acts upon a second piston, the work of which is transferred to the same shaft as the work of the piston in the combustion cylinder.

20 The accompanying drawings show an embodiment of a stationary motor of the present construction, comprising a two-cycle hydrocarbon motor and a steam motor connected with this to utilize a mixture of exhaust 25 gases and steam obtained in the manner just described. The improvement can equally well be adapted for four cycle motors with the proper modifications.

In the drawings,—

30 Figure 1 shows a vertical section through both cylinders and through the receiver along the line A—B in Fig. 4.

Fig. 2 shows a vertical section along the broken line C—D—E—F—G in Fig. 4, the 35 pistons being removed.

Fig. 3 shows the construction in plan, and Fig. 4 in horizontal section along the line H—I in Figs. 1 and 2.

Fig. 5 is an oblique elevation, partly in 40 vertical section, through the axis of the valves.

Fig. 6 is a fragmentary vertical section through the oil pump.

Fig. 7 is a fragmentary vertical section 45 through the valve 6.

The compressed air introduced into the working cylinder 1 of the hydrocarbon oil motor comes in contact with fuel oil introduced through the fine injection nozzle 2, whereupon this burns. The pressure medium arising therefrom expands until the piston 3 has sunk so far that the outlet ports 4 are uncovered (the position of the piston in Fig. 1). The used-up pressure medium 50 flows through these ports into the channel 5, in the outlet from which the relief valve

6 (Fig. 2) is arranged. After passing the valve, the pressure medium flows through a receptacle 7 of proper construction partially filled with water, which receptacle, on account of a certain relationship with the receiver in compound machines as regards construction and operation, is here called a receiver. In this receiver there is a certain amount of water, the proper amount of 60 which is determined through experiment. Through this water the combustion gases coming from the combustion cylinder of the oil motor, are allowed to flow and produce thereby steam, which mixes with the 65 combustion gases. The mixture is led into the channel 8 at the upper end of the receiver and flows out through the port 9, under control of a piston slide valve 10, which on its descent admits the mixture into a 70 port 11 which leads to the bottom of a second cylinder 12. In this cylinder the gas and vapor mixture acts upon the lower surface of a piston 13, which in the arrangement here shown is connected with the piston 3. 75

As indicated, the piston 13 preferably has a considerably larger diameter than the piston 3. As the piston 13 approaches its upper position, the piston valve 10 changes beforehand in the ordinary manner the direction of the flow, the connection between the ports 11 and 14 is opened, and the gas and vapor mixture is exhausted from the cylinder 12 through the ports 11 and 14 to the discharge pipe 15 which leads to a centrifugal condenser 16 (Fig. 2) of any ordinary construction. 80

The pistons 3 and 13, are by means of a piston rod 17, connected with a cross head 19 sliding in the guide 18, and this, by means of 95 the usual pin 20, is connected with the connecting rod 21 which drives the crank shaft 22. The piston rod and crosshead can, however, be replaced by a lengthened self-packing piston or plunger of such dimensions that the upper end of the connecting rod 100 is fastened in the piston in the usual way, the same as the link rod 23 is connected with the piston 24.

The cylinder 12 above the piston 13 serves 105 as an air compressor. The air compressed by the movement of the piston 13 upward passes through the port 25 under control of the valve 26 (which forms a continuation of the piston-valve 10) to the air receptacle 27. From this receptacle the air forces 110 itself through shut-off valve 28 into the

combustion cylinder 1 at the moment when the pressure in the latter cylinder sinks below the pressure of the air compressor, which happens during the very last part of 5 the downward piston stroke, when the outlet ports 4 communicate with the receiver. The air thus scavenges the cylinder.

The valve 6 is a check valve, so that the receiver 7, if the pressure in the cylinder 1 10 approaches the pressure in the receiver, is shut off from the combustion cylinder 1, so that neither water nor steam will flow into the cylinder 1. The construction of the valve 6 in detail may be as shown in Fig. 15 7, where the valve 6 is pressed down by a spring 6' re-acting against the casing 6''. The lower end 6''' of this casing limits the 20 lift of the valve. The cylinder 1, the exhaust gas and steam cylinder 12, and the valve device, are preferably within the receiver.

The control of the motor by the shaft 22 takes place by a reverse mechanism of the same kind as in steam engines for reversing from forward to backward, and vice 25 versa. This reverse mechanism, which is shown in Figs. 1 and 2, consists of an eccentric attached to the shaft 22, which is inclosed by an eccentric frame attached to a 30 lever 29, which is connected by means of a pin 30 with the link rod 31. The lower end of the latter is again by means of a pin 32 connected with the lower end 33 of the reverse arm, which end, in reversing, describes 35 a circular-shaped course with the axis of the reverse shaft 32 as center. The lever 29 drives the link rod 23 of the reverse mechanism, which by means of the hinge pin 35 is connected to the lower portion of 40 the piston valve rod 36, which latter portion is enlarged to a packed piston 24 closing off the space 14 downward. The movement from forward to backward, and vice versa, is obtained by throwing over the 45 reverse lever 37 in the direction of the arrows. The lever 37 is connected to crank arm 33 through a rock shaft 37^b turning in a bearing 37^a.

A safety valve 38 (Fig. 3) secures the receiver 7 from bursting on account of the 50 pressure ruling in the receiver.

The upper end of the valve piston rod 36 drives a super air compressor 40 which 55 draws compressed air from the chamber 27 through a port 41, compresses it to higher pressure, and expels it through a passage 42 which leads to the fuel injection nozzle 2 for spraying the fuel oil into the cylinder 1. At the same time air is driven from 60 40 through a tube 43 to a reservoir (not shown) for storing compressed air for use in starting the engine.

The compressor 40 is illustrated diagrammatically, the details as to valves, etc., not 65 being indicated, as such compressors are

well understood. For driving the compressor the valve rod 36 engages through a screw 45 screwed into its upper end, and nuts or screw collars 46, with a lever arm 44 projecting from a rock shaft 47 which has 70 an upturned arm 47' engaging the plunger of the compressor 40. The lever arm 44 acts upon another lever 49, the opposite arm of which engages a valve stem 50 in the fuel oil injector and lifts it at the proper 75 intervals for introducing the liquid fuel into the combustion cylinder 1, so that the fuel is sprayed into this cylinder by the high pressure air from the compressor 40 which enters through the channel 51. The oil-injecting pump may be constructed as shown in Fig. 6. The pump casing 48 receives the end of the shaft 47 which carries an eccentric pin or crank 47^a which moves in a slotted crosshead 47^b forming part of the 80 piston 47^c, the corresponding rod 47^d serving as a guide. As the piston 47^c reciprocates, oil is drawn from the casing through suction opening 47^e and forced out past the ball valve 47^f, and flows thence into chamber 51, from which, under control of the spindle 50, it enters through the nozzle 2 into the combustion chamber.

Water is admitted by a pipe 53, being drawn in by a plunger 52 carried on the 95 valve stem, and forced out into a passage 54, from which it flows into the receiver 7 which, as above stated, surrounds the combustion cylinder 1.

What I claim is:

1. The combination of an internal combustion motor and a steam motor with a receiver containing water, a passage leading the spent gases from the first motor to said receiver to vaporize the water, a loaded check-valve in said passage, a valve controlling the flow of mixed gases and steam from the receiver to said steam motor, and an air-compressor discharging into the first motor to scavenge its cylinder. 100

2. The combination of claim 1, in which the cylinder of said steam motor receives steam at one end and air at the other, so that the same piston serves for both the steam motor and air compressor. 110

3. The combination of claim 1, the steam motor and air compressor being connected to move in unison. 115

4. The combination of an internal combustion motor, a receiver containing water, a passage leading the spent gases from said motor to said receiver to vaporize the water, a steam motor, and an air compressor, the pistons of said motor and compressor being connected to move in unison, a valve controlling the flow of mixed gases and steam from the receiver to said steam motor, and a conduit leading the air from said compressor to the internal combustion motor. 120

5. The combination of an internal com- 130

bustion motor, a receiver containing water, a passage leading the spent gases from said motor to the receiver to vaporize the water, a steam motor, a valve controlling the flow 5 of fluid from the receiver to said steam motor, and an air compressor driven from the motors and discharging into the cylinder of the first motor to scavenge it.

6. The combination of claim 5, plus a 10 super-compressor for further compressing the air delivered from said compressor, and means for injecting the super-compressed air into the first motor.

7. The combination of claim 5, plus means 15 for forcing highly compressed air into the cylinder of the combustion motor together with fluid fuel.

8. The combination of an internal combustion motor of the two-cycle type, having 20 in its cylinder exhaust ports uncovered by the piston at the end of its stroke, a receiver containing water, a passage leading the spent gases from said exhaust ports into said receiver to vaporize the water, a steam 25 motor, a valve controlling the flow of mixed gases and steam from the receiver to said steam motor, an air compressor driven by said motors, and a valved passage from said compressor entering the cylinder of said first 30 motor, the valve thereof adapted to admit

compressed air to said cylinder at the end of the power stroke to scavenge the cylinder.

9. The combination of claim 1, plus a reversible slide valve mechanism controlling the flow to and from the steam motor and 35 air compressor.

10. The combination of claim 1, plus a reversible slide valve mechanism controlling the flow to and from the steam motor and air compressor, and a super-compressor driven 40 by said valve mechanism for further compressing the compressed air.

11. The combination of claim 1, in which the receiver partially incloses the cylinders of said motor and air compressor to cool 45 them and utilize the heat therefrom to generate steam.

12. A combined motor according to claim 1, having its combustion cylinder above and a larger steam cylinder beneath, and having 50 its receptacle for water and steam surrounding such cylinders so as to abstract heat therefrom.

In witness whereof, I have hereunto signed my name in the presence of two subscribing 55 witnesses.
